ATOMIZING DEVICE

Millard F. Saxton, Flint, Mich., assignor to The
Engineered Products Co., Flint, Mich., a cor-
poration of Michigan

Application August 17, 1950, Serial No. 180,051

9 Claims. (Cl. 299—120)

1

This invention relates to an atomizing device for converting liquids under pressure into a finely divided state such as for igniting, homogenizing or aerating the liquid.

It is an object of this invention to produce an atomizing device which is economical to manufacture and which, at the same time, produces a uniformly fine spray.

It is a further object of this invention to produce an atomizing device which is designed such that it can be calibrated very readily to produce a given flow of liquid with a minimum change in spray angle.

These and other objects of the invention will be better appreciated from a consideration of the following description taken in conjunction in the accompanying drawings in which

Fig. 1 is an elevational view of the atomizing device of this invention, parts being broken away to better illustrate the internal arrangement thereof.

Fig. 2 is a sectional view taken along lines 2—2 in Fig. 1.

Fig. 3 is a sectional view taken along lines 3—3 in Fig. 1.

Fig. 4 is a sectional view of the orifice plate taken substantially along lines 4—4 in Fig. 6.

Fig. 5 is a sectional view taken at right angles to the axis of the grooves in the retainer plate along lines 5—5 in Fig. 4.

Fig. 6 is a horizontal sectional view through the retainer plate taken along lines 6—6 in Fig. 4.

Fig. 7 is a fragmentary perspective view of the retainer plate.

The atomizing device of this invention generally comprises a body member in the form of a housing 10 which is externally threaded at one end as at 12 for connection with a source of liquid under pressure to be atomized. Housing 10 is internally bored as at 14, the bore being ensmalled at one end to provide a shoulder 16 and an opening 18 at the end of housing 10 opposite the threaded end 12. The bore 14 of housing 10 is internally threaded as at 20 to receive a threaded retainer 22. Retainer 22 is in the form of a hollow plug having a central inlet passage 24 formed as a blind hole in the threaded end of the retainer and is provided with a plurality of transversely extending ports 26 which communicate with the passage 24 to provide outlet ports. The inner end of retainer 22 has an external diameter less than the diameter of bore 14 such as to provide a circumferential passage 28 between the retainer and the housing 10 into which passage the ports 26 discharge.

2

Between the end face 30 of retainer 22 and shoulder 16 of housing 10 there is positioned an orifice plate 32 which is grooved circumferentially on one face as at 34 to interfit with shoulder 16. Groove 34 forms a reduced end portion 36 which projects through opening 18 in housing 10. Plate 32 is dimensioned such as to have a rather snug fit in bore 14 and is held in fixed position within housing 10 by retainer 22 which bears 10 with its end face 30 against the inner flat face 38 of the retainer. The outer face 40 of plate 32 is provided with a central orifice 41 of cylindrical form which is dimensioned to give a predetermined rate of liquid flow.

15 In the opposite face 38 of plate 32 there is formed a conical opening 42 which communicates at its reduced end with the orifice 41. In face 38 of plate 32 there is also formed a plurality of slots 44 which extend from the outer periphery of the 20 plate to the conical opening 42 in a direction generally tangential of opening 42. As is best illustrated in Figs. 5 and 7, slots 44 are triangular in cross section and the angle a between the side walls of slots 44 is preferably equal to the apex 25 angle b of opening 42. In the form of the invention shown, three slots 44 are shown. The number of slots provided and their size, of course, depends upon the flow required through the nozzle.

One of the important features of my invention 30 resides in the design of the slots 44. It will be observed that these slots are inclined to the inner face 38 of plate 32 or, in other words, the root 46 of each slot forms an angle c with the face 38. The angle c is determined such that slots 44 may 35 be cut with a tool which moves in an unconfined manner transversely across the face 38 of plate 32 without cutting into or nicking the opposite edge of opening 42. This is clearly illustrated in Fig. 4 where it will be seen that the root 46 of each slot extends along the line which clears the face 38 of plate 32 on the side of opening 42 which is opposite each groove 44.

With the parts assembled in the manner illustrated in Fig. 1, it will be noted that grooves 44 45 provide channels which connect the circumferential passage 28 with conical opening 42 and that the end face 30 of retainer 22 closes the open end of opening 42 so as to provide a conical chamber. Channels 44 are of triangular cross section which 50 reduces in area in a direction towards the conical chamber formed by opening 42 and end face 30 of retainer 22.

To atomize the liquid the nozzle is connected as by the threaded portion 12 with a source of liquid under pressure so that liquid of the desired

3

pressure is supplied to the opened or rear end of housing 10. The liquid flows into the central inlet opening 24 and is then conducted by the ports 26 to the circumferential passage 28 from which passage the liquid flows into slots 44 at an entry point adjacent the outer ends of the slots. The liquid then flows through the triangular slots into the chamber formed by opening 42 and out of the discharge end of the nozzle through the orifice 41. It will be noted that, because of the inclination of slots 44, the liquid tends to impinge against the end face 38 of retainer 22 and thus a desired turbulence of the liquid is obtained. Due to the generally tangential entry of the liquid into the conical chamber formed by opening 42, the liquid rotates in this chamber, gaining velocity as it spins towards the reduced end of this chamber and orifice 41. As the liquid leaves the orifice it stops spinning and is thrown out in small microscopic droplets 20 forming a hollow conical spray.

As has been stated previously, slots 44 are designed such that they can be cut by a simple machining operation such as by a rotating milling cutter. This form of slot is also desirable from the standpoint of calibration of the nozzle. I have found that with a nozzle constructed as described herein calibration is greatly simplified because the flow through the nozzle at a constant pressure can be either increased or decreased with no appreciable change in spray angle by simply lapping out orifice 41 when it is desired to increase the flow and by lapping face 38 of plate 32 when it is desired to decrease the flow.

The reason why my nozzle can be calibrated in this manner will be appreciated from a consideration of the following mathematical equations:

The spray angle of a nozzle of this type is determined by the following equation:

$$\frac{CL}{M} = \tan \frac{1}{2}\theta$$

The quantity of flow is determined by the equation

$$Q = CxMA\sqrt{P}$$

wherein

θ = The spray angle

C and C_x are constants for the particular formula of nozzles under consideration

$L = \frac{D_e}{D_o}$ = radius of entry point of slots
radius of orifice

$M = \frac{A_i}{A_o}$ = area of entry slots
area of orifice

P = Constant

Q = Quantity of fluid flow

When it is desired to increase the flow, the orifice diameter is increased by boring or lapping. Therefore the equation

$$L = \frac{D_e}{D_o}$$

changes to

$$L_i = \frac{D_e}{\frac{\pi}{4}(D_o + \Delta D_o)^2}$$

thus effecting a decrease in L.

However, since

$$M = \frac{A_i}{A_o}$$

then

$$M_i = \frac{A_i}{\pi(D_o + \Delta D_o)}$$

4

and therefore M is also decreased. Since the upper and lower factors in the spray angle equation stated above both change in the same direction, there is little change in spray angle when the rate of flow is increased by enlarging the orifice.

When it is desired to decrease the flow, the back surface 38 of plate 32 is lapped off. Since grooves 44 are of triangular shape, the reduction in area of these grooves is proportional to the square of the amount removed from surface 38. At the same time, the diameter of the spin chamber formed by opening 42 is reduced as a straight line functional because of its conical shape.

Since

$$L = \frac{R_c}{R_o}$$

then it follows that

$$L_i = R_c - \Delta \frac{R_c}{R_o}$$

and L is reduced. However, since

$$M = \frac{A_i}{A_o}$$

then

$$M_i = A_i - \Delta \frac{A_i}{A_o}$$

and M is also reduced. Therefore the equation

$$\frac{CL}{M} = \tan \frac{1}{2}\theta$$

changes to

$$\frac{C(L - \Delta L)}{\frac{R_o}{A_i - \Delta A_i}} = \tan \frac{1}{2}\theta$$

Here again the upper and lower factors of the equation change in the same direction and the spray angle tends to remain substantially the same when the flow is decreased by lapping the back face 38 of plate 32.

It will thus be seen that I have provided an improved atomizing device, the construction of which is advantageous not only from the standpoint of manufacture but also from the standpoint of operation and calibration. It will be readily appreciated that the operation of forming the slots 44 by a tool such as a rotating milling cutter is a very fast machining operation as compared to the conventional manner of forming a slot in a nozzle plate by coining or by milling to a stop which would be necessary where unconfined transverse movement of the cutting tool is not possible. Another advantage of my design is that the orifice plate may be machined from materials which are extremely hard, such as sapphire or tungsten carbide.

It will be noted that all of the sections of the orifice plate are well bolstered so that the use of a brittle material is not objectionable. The machining of the retainer plate can, of course, be performed by commercially recognized methods of the jewel processing industry.

The operating characteristics of my nozzle are also superior to conventional nozzles. Frictional losses are maintained at a minimum because of the tapered slots as compared with slots of uniform cross section. In addition, the orifice plate is designed to produce greater turbulence of the fluid. The conical chamber formed by opening 42 likewise imparts an improved spinning action to the fluid as it advances toward the orifice.

I claim:

1. In an atomizing device, a housing, a plate in said housing, said plate having a passageway extending therethrough, said passageway being of conical shape at one end and being ensnalled to form a cylindrical orifice at the other end, the face of said plate adjacent the conical portion of said passageway being substantially flat and having a plurality of slots therein extending from the periphery of said flat face at the outer end to the conical portion of said passageway at an angle inclined toward said face of said plate, and means within said housing closing the conical end portion of said passageway and forming passage means for admitting liquid to said slots adjacent the outer end thereof.

2. In an atomizing device, a housing, a plate in said housing, said plate having a passageway extending therethrough, said passageway being of conical shape at one end and being ensnalled to form a cylindrical orifice at the other end, the face of said plate adjacent the conical portion of said passageway being substantially flat and having a plurality of triangular slots therein extending from the periphery of said flat face at the outer end to the conical portion of said passageway at an angle inclined toward said face of said plate, and means within said housing presenting a wall portion closing the conical end portion of said passageway and forming passage means for admitting liquid to said slots adjacent the outer end thereof, said slots being inclined toward said wall at their inner ends whereby the liquid flowing therethrough is caused to impinge against said wall portion as the liquid enters said conical passageway.

3. In a nozzle for atomizing fuel, a housing, a plate in said housing having an orifice in one face thereof for discharging liquid as a spray from said housing, said plate having a conical concavity in its opposite face communicating at its reduced end with said orifice, said opposite face having a plurality of slots therein extending from the periphery thereof to said conical concavity, said slots extending generally tangentially of said conical concavity with the roots of said slots inclined toward said opposite face in the direction of said concavity, and means within said housing presenting a wall closing the enlarged end portion of said concavity at said opposite face and providing passage means for admitting liquid to said slots adjacent the outer end thereof, the roots of said slots being inclined toward said wall at the discharge end of the slots whereby the liquid flowing through said slots and into said conical concavity is caused to impinge against said wall.

4. The combination set forth in claim 3 wherein the slots are of triangular cross section and the angle included between the side walls of said slots is substantially equal to the apex angle of said concavity.

5. The combination set forth in claim 3 wherein said opposite face of said plate is flat and wherein said last mentioned means comprises a plug member threadedly engaged with said housing and having an end face contacting said opposite face of said plate.

6. The combination set forth in claim 5 wherein said end face of said plug is substantially flat and is smaller in diameter than said opposite face of said plate, said plug being hollow and having passageways extending from said hollow portion through the side wall thereof adjacent said end face.

7. The combination set forth in claim 3 wherein the root of said slots is inclined to said opposite face of said plate such that the slots may be formed with a cutting tool of unconfined lateral movement without cutting into said opposite face at a point beyond the intersection of said slots with said conical concavity.

8. The combination set forth in claim 3 wherein the root of each slot is inclined to said opposite face of said plate such that a line extended through said root at the discharge end of said slot passes through the enlarged end of said conical concavity without intersecting the side wall portion of said concavity opposite the discharge end of said slot.

9. An orifice plate for an atomizing device comprising a body portion having a passageway extending therethrough to opposite end faces of the plate, said passageway being of conical shape at one end and ensnalled to form a cylindrical orifice at the other end, the face of said plate adjacent said conical end of said passageway being substantially flat and having a plurality of slots therein extending from the periphery thereof to the conical portion of said passageway, said slots extending generally in a direction tangentially of said conical end of said passageway and extending along a line inclined toward said last mentioned face of said plate, the angle of inclination being such that the root of each slot when extended passes through the enlarged end of said conical portion of said passageway without intersecting the side wall portion of said passageway opposite the discharge end of each slot.
